IRA A. MANN, OF PITTSBURGH, PENNSYLVANIA.

PLUMBING-FIXTURE.

1,132,953.

Specification of Letters Patent. Patented Mar. 23, 1915.

Application filed October 3, 1912. Serial No. 723,678.

To all whom it may concern:

Be it known that I, IRA A. MANN, a citizen of the United States, residing at Pittsburgh, in the county of Allegheny and State 5 of Pennsylvania, have invented certain new and useful Improvements in Plumbing-Fixtures, of which the following is a specification.

The invention relates to the construction 10 of plumbing fixtures, and more particularly to closet constructions, although certain of the features of improvement are applicable to other sanitary fixtures involving the use of a bowl and a water seal. The construction 15 is particularly desirable in closets having integral traps and flushing rim bowls. The primary objects of the invention are; the provision of a plumbing fixture in which the danger of clogging at a point difficult 20 of access is eliminated; the provision of an improved structure in which the flushing may be accomplished under a relatively low pressure and with pressures which fluctuate widely; the provision of a construction in 25 which the quantity of water required for flushing is reduced to a minimum; and the provision of a construction in which the depth of the water seal may be made greater than that now commonly employed, without 30 interfering with the flushing operation even at relatively low pressures. Certain embodiments of the invention are illustrated in the accompanying drawings, wherein—

Figure 1 is a vertical section through the 35 center of my improved apparatus; Figs. 2 and 3 are detail plan views of two of the fixtures used in connecting the bowl to the outlet pipes; Fig. 4 is a plan view of the member employed for connecting the upper portion 40 of the bowl shelf to the piping at the rear of the partition; Fig. 5 is an elevation of the end of one of the bracket arms employed in the structure of Fig. 4; Fig. 6 is a section on the line VI—VI of Fig. 1, looking 45 in the direction of the arrow; Figs. 7 and 8 are sections similar to that of Fig. 6, but illustrating modified arrangements of the jet openings; Fig. 9 is a partial vertical section through a modified type of construction; Figs. 10 and 11 are vertical sections 50 through other modified forms of construction, and Fig. 12 is a fragmentary section of the wall of the outlet passage, and illustrates a modification of the structure illustrated in 55 Fig. 11.

Referring first to the general arrange-

ment of parts as illustrated in Fig. 1; 1 is the bowl which may be of any desired material—preferably vitreous material; 2 is the bowl cavity which may be of any desired contour; 3 is the outlet passage leading from the bowl cavity; 4 is the partition against which the shelf 5 of the closet rests; 6 is an inlet pipe for introducing the supply of flushing water, such inlet pipe supplying 60 the cavity 7 from which water is introduced into the passage 3 for flushing purposes, and into the rim cavity 8 via the passage 9; 10 is the discharge pipe; 11 is either a vent pipe or a capped member used only as a 65 supporting member for the top shelf of the bowl as hereinafter described; 12 is a T connection into which the passage 3 discharges and which connects the pipes 10 and 11; 13 is a collar in two parts which encircles the 70 pipe 11 and is connected to the shelf 14 as hereinafter described; and 15, 16, and 17 are connecting elements for securing the bowl to the T connection 12, such connection being later more particularly described. The 75 invention is illustrated as applied to a closet with a partition between its members, but it will be understood that the invention is applicable not only to other types of closets, but also to other types of sanitary fixtures 80 employing a bowl and a water seal. The inlet end of the passage 9 leading to the rim cavity lies below the level of the water seal, thus preventing the access of sewer gases to 85 the rim cavity.

One of the important features of my invention is the making of the inlet end of the passage 3, or in other words, the end which connects with the bowl cavity 2 as indicated at the point 18, of less diameter than the 90 succeeding portions of the passage. For instance, in the case of a bowl in which the main portion of the passage 3 is made of the standard diameter of three inches, the contracted inlet end may in practice be made as 95 small as two inches. I have found that this arrangement secures two important results. In the first place a more effective flow through the passage is secured, with a lower pressure of the flushing water, and in the 100 second place any stoppage or clogging which may occur in the passage is made to occur at the contracted inlet end 18 instead of occurring farther along in the passage, it being obvious that any obstruction which will 105 pass the portion 18 will pass through the larger portion of the passage farther along.

without difficulty. The portion 18 of the passage is of course readily accessible for cleaning, without special tools, so that the closet may be readily relieved from any obstruction, which is not the case in the ordinary type of closet in which the obstruction always occurs at some point so remote from the inlet end of the closet that great difficulty is usually experienced in freeing the closet from its obstruction, the services of a plumber usually being required for this purpose, and requiring the removal of the closet from its seat in many cases. The length and position of the contracted portion of the passage may be somewhat varied, the only requirement being that it be located closely adjacent the outlet from the bowl cavity and readily accessible from the interior of the bowl.

20 Another feature of invention resides in the arrangement of the flushing jet with respect to the outlet passage 3. As indicated in Fig. 1, the contracted portion 18 of the passage is surrounded by a cavity 19 communicating with the cavity 7, and this cavity 19 is provided with a plurality of jet or spray discharge openings 20 arranged at the periphery of the passage and adapted to project a supply of flushing water in the form of an annular jet along and in contact with the walls of the enlarged portion of the passage. As hereinafter described, this flushing arrangement is preferably employed in connection with additional flushing means for entraining the central portion of the body of water in the passage and carrying it to the soil pipe. The primary object of the jets or sprays of water issuing from the peripheral openings 20 is not so much to entrain the body of water in the passage as it is to eliminate the friction between such body of water and the interior surface of the passageway, it being true, however, that there is a certain amount of entraining action, and that these jets or sprays from the openings 20 might be employed with advantage even though not placed at the exact periphery of the passage and if not directed exactly parallel with the walls of the passage. In order to entrain and force along the central portion of the body of water in the passage 3, the converging passageways 21 are provided leading from the cavity 19, the convergence of such passageways being indicated by the dotted lines 22. The jets of water from these passages or openings 21 serve to entrain and propel the main body of water through the passage 3, while the water propelled through the openings 20 serves to reduce the friction incident to the passage of the body of water through the passage. This arrangement has been found to permit of the use of a relatively very low pressure of flushing water, the bowl being effectively flushed

when such low pressure is used, and the noise incident to the operation of the apparatus being correspondingly reduced. It will be noted that the contraction of the inlet end of the passage 3 serves to permit a convenient and effective arrangement of the flushing openings 20 and 21, as the thickness of wall incident to the contraction of the passage is utilized to carry the supply cavity 19 and the openings 20 and 21.

The vertical weight of the bowl is carried by the connecting nipple 15 which is screw threaded into the T member 12 at its outer end, and is fitted into the vitreous material at its other end, the soft packing 23 serving to secure a tight joint between the material of the bowl and the nipple 15. A packing 15' is provided around the outer end of the nipple. In order to tighten the metallic packing 23 the collar 17 shown in Fig. 3 is employed, such collar bearing against the packing 23 and being pulled tightly into position to compress such packing by means of bolts 24 which extend through the wings 25 of the collar and through the shelf of the bowl, permitting of the tightening of the packing 23 without removing the bowl from the supporting partition. The bowl is held against bearing too hard against the supporting partition, by means of the other collar 16 shown in Fig. 2, such collar being screwed onto the nipple 15 and having the projecting lugs 26 which engage the rear face of the bowl. The thrust of the bowl is therefore taken by the piping at the rear of the partition instead of by the partition which may be relatively light and frail.

The connection whereby the strain of supporting the shelf 14 from the piping 11 is taken, is illustrated in plan view in Fig. 4. From this view it will be seen that the bracket 27 carrying the inner half of the collar 13 is provided with a pair of slotted arms 28 (Fig. 5), which slotted arms receive the threaded members 29 which are flattened on the sides as indicated at 30, to prevent the rotation of the members in the slots carried by the arms 28. The members 30 are held locked in position by means of the nuts 31 and 32 on opposite sides of the arms 28. By this arrangement the position of the front ends 33 of the members 29 may be readily adjusted and locked in position. The shelf is secured to the ends 33 of the members 29 by means of the pair of bolts 34. It will be seen that with the heads 33 properly positioned flush with the outer face of the partition 4 the partition cannot be injured no matter how tightly the bolts 34 are screwed into position, the heads 33 taking the thrust of the shelf 14.

Fig. 7 indicates a modification of the jet opening arrangement shown in Figs. 1 and 6, such modification consisting in making

the inner set of openings 21' circular in cross section, instead of rectangular as in the case of the openings 21 in the construction of Figs. 1 and 6. The outer or peripheral openings 20 are made as in the construction of Figs. 1 and 6.

Fig. 8 illustrates another modification of the jet opening construction, such modification consisting in using the central circular openings 21 the same as in the construction of Fig. 7, but in providing a continuous slot 20' to take the place of the series of openings 20 in the constructions of Figs. 1, 6, and 7.

Fig. 9 also illustrates a construction constituting a modification of the structure of Fig. 1 in so far as the flushing means is concerned. This structure instead of employing the series of converging passages 21 for entraining the central portion of the body of liquid in the passage 3 as is done in Fig. 1, dispenses with such passages and in their place a central jet opening 35 is employed, such jet opening being connected with the flushing cavity 7 by means of the passageway 36. The peripheral jet openings 20 are employed just as in the construction of Fig. 1, and the result achieved is substantially the same.

Fig. 10 illustrates a somewhat different arrangement for supplying flushing water to the ring cavity 19' and to the rim cavity 8. In this construction water is supplied to a cavity 37 and thence via a passageway 38 at the side of the bowl to the cavity 19' from which a flushing of the passage 3' is secured by means of openings 20 and 21 as in the construction of Fig. 1. Water is conducted from the ring cavity 19' to the rim cavity 8 by means of a passageway on the side of the bowl opposite to the passageway 38, such passageway being indicated by the dot and dash lines 39. It will be noted that this construction illustrates the application of the invention to a fixture with an integral pedestal resting on the floor, the outlet of the bowl leading to a floor connection instead of to a wall connection, without a partition between.

Fig. 11 indicates a modified type of the invention as applied to a plumbing fixture. In this structure the flushing cavity 7' is connected to the rim cavity 8' by means of the passage 40 extending through the side of the bowl, and the flushing of the outlet passage 3' is secured by means of a central jet opening 41 for engaging the central portion of the body of liquid in the passage 3', and by the series of inclined passages 42 for decreasing the friction of the body of water at the sides of the passage, the openings 42 being preferably arranged in the staggered form illustrated.

Fig. 12 illustrates a modified form of the construction illustrated in Fig. 11, the wall

43 of the passage being in this case provided with a series of openings 44 for the flushing water, such openings being so arranged as to direct the flushing water substantially parallel with the surface of the wall. Various 70 other modifications might be made without departing from the spirit of the invention which is directed broadly to the contraction of the inlet end of the outlet passage, and to the provision of the means at or adjacent 75 the periphery of the outlet passageway for securing a supply of the flushing liquid along the walls of the passage way, and thus reducing the friction incident to the passage of the body of liquid through the passageway.

The general method of operation of all the types of apparatus as heretofore described is substantially the same, the contents of the bowl being withdrawn by reason of the drag imposed through the jets forced along the upwardly inclined passageway 3, rather than by siphonic action as in the case of the ordinary type of closet. In the operation of the construction as illustrated in Fig. 1, the 90 flushing water supplied through the pipe 6 first passes through the openings 20 and 21, thus securing a substantially instantaneous and vigorous movement upward of the body of the water in the passage 3, which movement as heretofore explained, is facilitated by the removal of friction at the surface of the passage, which permits the main driving or entraining force from the openings 21 to carry the body of water upward through the 100 passage. This movement of the water through the passage 3 of course produces a vigorous suction action at the reduced end 18 of the passage, thus securing an effective cleansing of the bowl. Substantially simultaneous with this action a portion of the water is directed to the flushing rim which extends around the upper portion of the bowl, the downflowing water from this rim giving the interior of the bowl a thorough 110 scouring as the main body of water in the bowl flows out through the outlet passage.

Having thus described my invention and illustrated its use, what I claim as new and desire to secure by Letters Patent, is the 115 following.

1. In combination in a plumbing fixture, a bowl, an inclined discharge passage, inlet jet means opening into the discharge passage and encircling such passage and directed in substantial parallelism with the walls of the discharge passage at the periphery thereof, and other jet means opening into the discharge passage and directed obliquely with respect to the walls of the 120 discharge passage.

2. In combination in a plumbing fixture, a bowl, an inclined discharge passage, an inlet jet means opening into the discharge passage and encircling such passage and di- 130

rected in substantial parallelism with the walls of the discharge passage at the periphery thereof, and other jet means for supplying water longitudinally of the discharge passage but inside of the first mentioned jet means and spaced away from the periphery of the passage.

3. In combination in a plumbing fixture, a bowl, a discharge passage having a reduced 10 inlet portion leading downward from the bowl and then inclined upwardly and a main portion of larger diameter than the inlet portion and inclined upwardly, the said portions merging into each other, an annular supply passage in the wall of the reduced inlet portion of the passage and ex-

tending around said portion, and jet inlet means leading through the wall of the discharge passage at the point where the two portions of the passage merge, the jet inlet means extending around the discharge passage and being directed in substantial parallelism with the walls of the said main portion of the discharge passage.

In testimony whereof I have hereunto 25 signed my name in the presence of the two subscribed witnesses.

IRA A. MANN.
